Primary Examiner — Rosemary K Tarcza*Assistant Examiner* — James Thorn, Sr.(74) *Attorney, Agent, or Firm* — Luedeka Neely Group, P.C.(57) **CLAIM**

The ornamental design for a table with extendable tabletop, as shown and described.

DESCRIPTION

FIG. 1 is a top perspective view of the table with extendable tabletop;

FIG. 2 is a left side elevation view of the table with extendable tabletop;

FIG. 3 is a right side elevation view of the table with extendable tabletop;

FIG. 4 is a front elevation view of the table with extendable tabletop;

FIG. 5 is a rear elevation view of the table with extendable tabletop;

FIG. 6 is a top plan view of the table with extendable tabletop;

FIG. 7 is a bottom plan view of the table with extendable tabletop; and,

FIG. 8 is a bottom perspective view of the table with extendable tabletop.
